His Attorney.

UNITED STATES PATENT OFFICE

PAUL D. ANDREWS, OF SCHENECTADY, NEW YORK, ASSIGNOR TO GENERAL ELECTRIC COMPANY, A CORPORATION OF NEW YORK

REGULATING MEANS FOR HIGH POWER ELECTRIC DISCHARGE AMPLIFIERS

Application filed April 12, 1930. Serial No. 443,876.

The present invention relates to means for regulating electric discharge amplifiers and more particularly, it relates to means for regulating amplifiers employing multi-grid electric discharge devices arranged to transmit relatively large amounts of energy such as are employed in radio transmitter circuits and the like.

High power amplifiers of this character having multi-grid amplifier devices are provided with positive biasing voltages which are applied to the additional grids of the tubes for the purpose of controlling the operating characteristics. The exact amount of positive biasing voltage which is supplied to the additional grid in a multi-grid tube or electric discharge device, varies with different types of tubes and also with different applications of the same type of tube, but this voltage is ordinarily approximately 20 to 35 per cent of the D. C. plate voltage used with a tube of the four-element type in that particular application.

If the positive biasing voltage applied to the additional grid is too low in value, the impedance of the tube under operating conditions will be too high for efficient operation and the amplification realized from the tube will be small. If, however, this positive biasing voltage is too high in value, the screen grid or space charge grid, as the case may be, will tend to overheat and to draw too high a current from the biasing source. This constitutes an unnecessary drain on the electron emission of the tube filaments and if considerable overheating of the additional grid takes place, it may also result in liberating possible gases from the material constituting this additional grid.

In extreme cases, the additional grid may even become so hot as to become fused and permanently damaged. This is particularly true in transmitting circuits where relatively large amounts of power are controlled by the tubes. Hence, the control of the biasing voltage for the additional grids of amplifiers employing multi-grid electric discharge devices is important.

Several methods are in use for obtaining the necessary positive biasing voltage for the

additional grid of tubes such as the four-element type in an amplifier circuit. Such tubes, as is well understood, are provided with a grid between the cathode and the anode and another grid between the first named grid and the anode. One such method comprises applying directly to the additional grid, whether it be the one adjacent the cathode or the second named grid, a suitable D. C. biasing voltage from a generator or biasing battery source, an average voltage value being selected in order to provide the best average operating condition over the various conditions under which the tube is required to operate. A signal or A. C. control potential may be applied to the other grid.

As is well known, normal screen grid operation is had when the signal is applied to the first or normal control grid and space charge grid operation is had when the signal is applied to the second grid, the positive biasing potential being applied in each case to the remaining grid.

With the direct application of a positive biasing voltage to the additional grid, it has been found that under certain operating conditions the tube tends to draw a heavy plate current, and that as a result, the D. C. current drawn by the additional grid will decrease to a very low value and may even become reversed.

In general, it may be said that in the operation of an amplifier including a multi-grid electric discharge device such as a four-element tube, with a positive biasing potential applied to the additional grid directly from a source of potential, as the D. C. plate current drawn by the tube decreases, the corresponding D. C. current drawn by the additional grid will tend to increase almost in proportion. In such a case, it will frequently be found that the energy dissipated from the additional grid in the tube will be excessive and will result in seriously overheating this grid.

It is for the above reasons that another method of operating a multi-grid electric discharge device such as a screen grid or space charge grid tube in an amplifier has

been followed to a greater extent and is used extensively in transmitting circuits. The positive biasing voltage for the additional grid is obtained from a higher voltage source 5 through a high resistance, a resistor sufficiently high in resistance value being placed in the biasing circuit to reduce the D. C. potential of the source to approximately the correct value for best operation of the amplifier stage under the various operating conditions.

The above described arrangement always insures a sufficiently high positive biasing potential or voltage for the additional grid 15 so that under various conditions of operation the potential applied to this grid is still always sufficiently high to cause the current drawn by this grid to flow in the proper direction.

20 While this arrangement has the advantage that the lower the current drawn by the additional grid tends to become, the higher the positive biasing potential applied to the grid will become, it is inherently inefficient 25 in that a higher value of supply voltage is required and a considerable energy loss must at all times occur in the series resistor used. For use in power amplifier circuits for transmitters and the like the series resistor must 30 necessarily be of a high value, for example, in the order of 50,000 ohms, and a resistor of the value when required to dissipate any appreciable energy is somewhat of a problem.

35 In view of the disadvantages of the direct method of applying a required operating voltage to a grid of a multi-grid electric discharge device such as that of the type above described, and of the series resistance 40 type of control of such voltage, it is the object of the present invention to provide an improved method of applying a biasing potential or voltage to a grid of a multi-grid electric discharge device for the purpose of 45 regulating an amplifier in which said device is included, and an improved circuit control means for effecting such regulation.

The invention will be better understood 50 from the following description when taken in connection with the accompanying drawing, and its scope will be pointed out in the appended claims.

In the drawing, the figure is a schematic wiring diagram of an amplifier stage including 55 a multi-grid electric discharge device provided with a regulating means embodying the invention.

Referring to the drawing, 5 is an electric discharge device of the four-element type 60 having a hot cathode 6, a control electrode or grid 7, an anode 8 and an additional grid 9. By way of example, this is a type of electric discharge device commonly known as a screen grid tube in which grid 9 is adjacent 65 the anode and is employed as a biasing elec-

trode, while grid 7 is the normal control electrode. It serves to illustrate any multi-grid electric discharge device having a grid which requires a controlled current at a predetermined range of applied potential.

The tube is included in an amplifier circuit provided with an input circuit indicated at 10 and an output circuit indicated at 11. The input circuit is connected with the control grid 7 and includes a grid-lead reactor 12 and a grid-leak resistor 13 to which is applied a suitable negative biasing potential or voltage as indicated at 14. An alternating current input control voltage is applied to grid 7 and the input circuit 10 through a coupling capacitor 15 and an input lead 16. The input lead 16 may be connected to any suitable source (not shown) of controlling or excitation alternating current potential for the amplifier stage.

The output circuit 11 is connected with the anode 8 and includes a tuning inductance 17 and a tuning capacitor 18 in shunt therewith, together with a suitable by-pass capacitor 19 connected between the low potential end of the output circuit 11, as indicated at 20, and a cathode return lead 21 which is grounded, as indicated at 22.

Inductance 17 and tuning capacitor 18 constitute a tuned circuit from the high potential end of which output alternating current energy from the amplifier may be taken through a suitable coupling capacitor 23 and an output lead 24 connected therewith. The by-pass capacitor 19 serves to maintain one end of the tuned anode circuit at ground or filament potential with respect to the audio or radio frequency current which traverses the output circuit. A positive operating voltage for the anode or output circuit 11 is supplied thereto through a suitable supply lead 25 to which a positive operating potential is applied, as indicated at 26.

In accordance with the invention, a positive biasing potential is applied to the additional grid or the grid requiring an applied operating potential, which in the present example is grid 9, through a supply lead 27 from a supply source of positive biasing potential as indicated at 28. Supply lead 27 is suitably by-passed adjacent grid 9 by a capacitor 29 connected between said lead and the cathode return lead 21, as indicated. Capacitor 29 is so selected that it possesses a low reactance at the operating frequency of the amplifier stage and serves to maintain the additional grid at ground or cathode potential as regards any A. C. potential.

Inserted in supply lead 27 is a regulating or control device 30 which provides a series regulating resistance in the positive biasing circuit. The resistance characteristic of the device 30 is such that it does not maintain a constant value when a varying current flows therethrough, but automatically varies in re-

sistance value in accordance with the various operating conditions which may tend to effect adverse changes in the applied potential on grid 9, to provide an optimum operating condition for the tube. In other words, its resistance value varies in response to changes in the current flow through it, and may be considered to be of the "ballast" type which tends to maintain through it a current which varies between relatively narrow and safe limits.

Such an automatically regulating resistance is easily applied to any supply voltage circuit for an additional grid in an amplifier stage by merely inserting such a device in circuit therewith. It does not, therefore, require further changes in the circuit than are necessary for the use of the ordinary series resistance hereinbefore mentioned, which has operating disadvantages hereinbefore described.

By way of example, the regulating device 30 may be provided by the filament of a standard 10 watt, 120 volt, tungsten filament, incandescent lamp of the "Mazda" type which are readily available commercially. The filament of such a unit possesses a cold resistance of only about 110 ohms, while the filament of the same lamp when 30 operating under normal rated voltage and current condition, possesses a hot resistance of over 1400 ohms. It is, therefore, readily adapted for the automatic control of the biasing voltage for the additional grid of an amplifier device of the above type. It is obvious that any desired value of regulating resistance may by this means be provided by providing the proper size of lamp or by properly combining the filaments of two or 40 more lamps in series parallel relation.

It will readily be seen that as the current drawn by the additional or bias potential grid of the tube tends to become excessively high, the resistance of the series control device 30 becomes rapidly higher and easily prevents this current from reaching an excessive value. On the other hand, as the current drawn by the additional grid would tend to become very low under certain operating conditions, the resistance of the series regulating device becomes lower and lower thereby tending to maintain the current more constant than would an ordinary resistor, and consequently the voltage applied 50 to the additional grid is increased while at all times the energy loss in the control device is automatically maintained at a minimum value.

Assuming that the positive biasing voltage applied to the additional grid has been properly selected initially, it is then readily possible to establish an operating condition under which the current drawn by the additional grid will never reverse and also will 60 never reach an excessively high condition.

Thus, it is at once evident that this method of obtaining the positive biasing voltage for the additional grid in an amplifier tube of this character provides more favorable operating conditions than either of the known 70 methods hereinbefore described.

Instead of employing a filament of a standard incandescent lamp or a plurality of such lamps in series parallel arrangement, a somewhat greater regulating characteristic may 75 be obtained by employing the filament of one of the so-called "ballast" or constant current type of lamps. As is well known, the filament of the latter type of lamp operates generally in a gas filled bulb and provides 80 a still greater resistance variation as the current through it is varied. The principle of operation is, however, the same in either case.

Any suitable resistance or resistor unit or device may, however be used which unit or device possesses the desired feature of automatically varying its resistance value dependent upon and in accordance with the current passing through it.

It will be seen that the above-described 90 method of applying an automatically adjustable positive biasing voltage or potential to the additional grid in a four-element amplifier tube, for example, may apply equally well to either the screen grid or to the space 95 charge grid type of tube, and that the tube may be operated as either an audio or a radio frequency oscillator or amplifier, or in any other capacity to which such made tube may be applied.

It will be appreciated that if a reverse regulating action to that described in the foregoing is found desirable in certain special applications, the same may readily be obtained by substituting for a regulating device having a positive resistance characteristic, such as that described, a regulating resistance having a negative coefficient of resistance. Such a device is found in a lamp of the carbon filament type, for example. In 110 either case, however, the grid of the tube which is supplied with a positive biasing voltage receives a current at a voltage controlled by a device which in itself is automatically adjustable in accordance with a tendency of 115 the current to increase or decrease.

From the foregoing description it will be seen that with means for applying a positive biasing potential to a grid of a multi-grid electric discharge device, the disadvantages 120 accompanying former methods are obviated. For example, if the tube tends to draw a heavy plate current which is ordinarily accompanied by a tendency for the D. C. current 125 drawn by the biased or additional grid to decrease or to become reversed, this action is prevented by the rapidly increasing application of voltage from the source as the resistance of the regulating device rapidly decreases with decreased current flow. Like- 130

wise, as the D. C. plate current drawn by the tube decreases and the corresponding D. C. current drawn by the additional grid tends to increase almost in proportion as in the usual case, the energy dissipated by the additional grid under such operating conditions will be prevented from becoming excessive and from overheating the grid by the rapidly increasing value of the resistance of the regulating device as the current tends to increase. The life of the tube is therefore greatly prolonged and operating conditions are improved.

It will further be seen that a regulating system embodying the invention obviates the inefficiency accompanying the use of an ordinary series resistor of the type hereinbefore mentioned and prevents the excessive loss of energy which occurs in such a series resistor.

As the resistance of the regulating device is automatically variable, it is required to dissipate only as much energy as is necessary to effect regulation. Furthermore, an excessively high and dangerous positive potential is prevented from being applied to the grid when such tube is "cut off" as may occur during the telegraphic keying of an amplifier stage such as that of the present example.

What I claim as new and desire to secure by Letters Patent of the United States is:

1. The combination with an electric discharge device having a control grid, a cathode, an anode, and an additional grid, of means for applying a positive biasing potential to said additional grid, said means including a voltage supply circuit and a constant current device in series with said supply circuit.

2. The combination with an electric discharge device having a control grid, a cathode, an anode, and an additional grid, of means for applying a positive biasing potential to said additional grid, said means including a voltage supply circuit and a regulating device in series with said supply circuit, the resistance of which device automatically varies sufficiently in accordance with the flow of current through it to cause said biasing potential applied to said additional grid to be maintained within a predetermined desired range.

3. The combination with a multi-grid electric discharge device, of means for automatically applying a positive biasing potential to a grid thereof, said means including a supply lead adapted to be connected to a source of positive potential, and a regulating device connected in said supply lead, said device having a positive coefficient of resistance, whereby as the current flowing to said grid increases, the resistance of said device increases in proportion thereto.

4. The combination with an electric discharge device having a control grid and an additional grid, of means for applying a

positive biasing potential to said additional grid, said means including a supply circuit and a regulating device connected in series therewith, said regulating device being of the ballast lamp type whereby its resistance varies in accordance with current flow therethrough.

5. The combination with an electric discharge device having a cathode, an anode, a control electrode, and an additional electrode requiring the application of an optimum value of positive biasing voltage thereto for the normal operation of said device, of a lead for supplying a biasing potential to said additional electrode, and a regulating device connected in said supply lead, said device having a resistance value which varies in dependence upon the current flowing through it.

6. The combination with an electric discharge device having a cathode, an anode, a control electrode, and an additional electrode requiring the application of an optimum value of positive biasing voltage thereto for the normal operation of said device, of an input circuit connected with the control electrode, a tuned output circuit connected with the anode, a by-pass capacitor providing a connection between the low potential end of said output circuit and the cathode, a lead for supplying a biasing potential to said additional electrode, a by-pass capacitor providing a connection between the additional electrode and said cathode, and a regulating device connected in said supply lead, said device having a resistance value which varies in dependence upon the current flowing through it.

7. The combination with an electric discharge device having a control grid, a cathode, an anode, and an additional grid, of means for applying a positive potential to said anode, and means for applying a positive biasing potential to said additional grid including a supply lead connected to a source of positive potential and a regulating device connected in circuit with said supply lead, the potential applied to said regulating device from said source being substantially less than the potential applied to said anode, the resistance of said device automatically varying sufficiently in accordance with the flow of current therethrough to cause said biasing potential applied to said additional grid to be maintained within a predetermined desired range.

8. The combination with an electric discharge device having a control grid, a cathode, an anode, and an additional grid, of means for applying a positive potential to said anode, and means for automatically applying a positive biasing potential to said additional grid including a supply lead connected to a source of positive potential and a regulating device connected in said supply lead, said regulating device having a posi-

tive coefficient of resistance whereby as the current flowing to said additional grid increases the resistance of said device increases to prevent excessive current flow to said additional grid, the potential applied to said regulating device from said source being substantially less than the potential applied to said anode whereby the potential of said additional grid is limited to a safe value.

10. In witness whereof, I have hereunto set my hand this 11th day of April, 1930.

PAUL D. ANDREWS.
